(57) **CLAIM**

The ornamental design for a packaging container, as shown and described.

DESCRIPTION

FIG. 1 is an upper left perspective view showing the top, front and left side of the packaging container of my new design; FIG. 2 is a front view thereof;

FIG. 3 is a top view thereof;

FIG. 4 is a left-side view thereof, the right side being the mirror image thereof;

FIG. 5 is a rear view thereof;

FIG. 6 is bottom view thereof;

FIG. 7 is an upper right perspective view of the packaging container in an opened position showing rack inserts;

FIG. 8 is a top perspective view of the design of FIG. 7, showing a full view of the sides and bottom of the interior of the packaging container of FIG. 7;

FIG. 9 is a perspective view with the racks removed from the lid and the inside, but showing corresponding rings the rack is inserted into;

FIG. 10 is a top perspective view of the design of FIG. 9, showing a full view of the sides and bottom of the interior of the packaging container of FIG. 9;

FIG. 11 is a perspective view in an opened position of the rack in an alternate position; and,

FIG. 12 is a top perspective view of the design of FIG. 11, showing a full view of the sides and bottom of the interior of the packaging container of FIG. 11.
